UNITED STATES PATENT OFFICE.

JOHN VENHUIZEN, OF HOLLAND, MICHIGAN.

DESIGN FOR A BEET-THINNER.

SPECIFICATION forming part of Design No. 32,403, dated March 27, 1900.

Application filed August 7, 1899. Serial No. 726,412. Term of patent 7 years.

To all whom it may concern:

Be it known that I, JOHN VENHUIZEN, a citizen of the United States, residing at Holland, in the county of Ottawa and State of Michigan, have invented and produced a new and original Design for Beet-Thinners, of which the following is a specification, reference being had to the accompanying drawing, forming part thereof.

10 As shown in the drawing, the leading or material feature of my design consists of a plate A, of substantially-rectangular outline, provided on each of its narrower sides with projecting points B B B B B and beveled edges 15 C C C C C C C and on each of its longer par-

alleled sides with curved unbeveled edges D D. The handle E rises from the center of plate A and is curved, as shown.

Having described my invention, what I claim as new, and desire to secure by Letters 20 Patent, is—

The design for a beet-thinner, as herein shown and described.

In testimony whereof I have signed my name to this specification in the presence of 25 two subscribing witnesses.

JOHN VENHUIZEN.
